DESIGN FOR A TEXTILE FABRIC

Eugene S. Ross, New York, N. Y.

Application October 3, 1935, Serial No. 58,811

Term of patent 3½ years

To whom it may concern:

Be it known that I, Eugene S. Ross, a citizen of the United States, residing at 450 Seventh Avenue, Borough of Manhattan, city, county, and State of New York, have invented a new, original, and ornamental Design for a Textile Fabric, for which the following is a specification, reference being had to the accompanying drawing, forming part thereof.

The figure is a plan view of a piece of textile fabric showing my new design.

I claim:

The ornamental design for a textile fabric substantially as shown.

EUGENE S. ROSS.
